UNITED STATES PATENT OFFICE.

DWIGHT L. SMITH, OF WATERBURY, CONNECTICUT.

BUCKLE.

SPECIFICATION forming part of Letters Patent No. 439,436, dated October 28, 1890.

Application filed May 19, 1890. Serial No. 352,354. (No model.)

To all whom it may concern:

Be it known that I, DWIGHT L. SMITH, of Waterbury, in the county of New Haven and State of Connecticut, have invented new Improvements in Buckles; and I do hereby declare the following, when taken in connection with accompanying drawings and the letters of reference marked thereon, to be a full, clear, and exact description of the same, and which said drawings constitute part of this specification, and represent, in—

Figure 1, a front view of the buckle; Fig. 2, a rear view of the same; Fig. 3, a vertical section on line $\alpha\alpha$ of Fig. 1; Fig. 4, the frame detached; Fig. 5, the lever detached; Fig. 6, the clamping-bar detached; Figs. 7 and 8, modifications.

This invention relates to an improvement in that class of buckles adapted for suspenders and similar garment purposes, and in which the buckle is formed, principally, from wire, and particularly to that class in which engagement is made by a swinging lever, the object being a simple construction for the hinging of the lever to the frame; and the invention consists in the construction, as hereinafter described, and particularly recited in the claim.

The frame, as seen in Fig. 4, is made from a single piece of wire, and consists of an upper bar a , a lower bar b , and two ends $c c$. The lower bar b is preferably bent so as to form a hook d as an integral part thereof. The two ends $c c$ of the frame are each constructed with U-shaped inward bends, forming recesses e , opening outward, the width of the recess thus formed between the two sides of the U being substantially equal to the diameter of the wire employed in the formation of the lever. The lever is constructed as seen in Fig. 5. It is made from wire, bent preferably so as to form an eye f to swing over the hook d . At its upper end it is constructed with inwardly-turned trunnions $g g$, corresponding to the recesses $e e$ formed in the side of the frame, as before described, and so as to set therein between the two sides of the said recesses $e e$, as seen in Fig. 3. A clamping-jaw h is made from sheet metal, this clamp being shown detached in Fig. 6. This bar is of a length corresponding to the distance between the two ends of the frame. Upon its upper side, at each end, is a projecting tongue

i , with corresponding projecting tongues l upon the opposite or lower edge. Between 55 these tongues $i l$ the jaw is preferably serrated, as also seen in Fig. 6. After the lever has been set in place so as to bring the trunnions or pivots $g g$ into the recesses $e e$ in the sides of the frame, the clamping-bar is set in 60 place and so as to bring the ends of the bar over the recesses $e e$ and the pivots. Then the tongues $i l$ are bent and closed around the inward projections forming the U-shaped recesses, as seen in Figs. 1, 2, and 3, and so as 65 to inclose the said recesses $e e$ and secure the pivots of the lever therein, but yet leave the lever free to swing on said pivots toward and from the clamping-plate. In the formation of the lever it is bent so as to form a 70 clamping-bar m , corresponding to the jaw h .

The invention is not to be understood as limited to producing the clamping-bar by means of the serrated jaw h and the bar m of the lever, as the lever also may be provided 75 with a jaw n , (see Fig. 7,) this jaw being formed as a part of a sheet-metal plate o , secured upon the face of the lever and so as to coact with a correspondingly-shaped jaw h on the body. In this case both the jaws n and h are 80 turned toward each other, as seen in Fig. 8.

I do not wish to be understood as claiming, broadly, a buckle consisting of a wire frame constructed with inwardly-turned U-shaped bends in the ends, as such, I am aware, is not 85 new; but

What I do claim is—

A buckle having a frame made from wire, composed of the upper bar a , the lower bar b , and two ends $c c$, the said two ends each 90 constructed with an inward U-shaped bend, forming recesses $e e$, opening outward, combined with a lever also made from wire, its two upper ends turned inward to form pivots $g g$, corresponding to the said recesses $e e$ in 95 the ends of the frame, and a sheet-metal clamp constructed with tongues i upon one side and l upon the opposite side, closed around said U-shaped projections and so as to inclose the said pivots in the said recesses e , substantially 100 as described.

DWIGHT L. SMITH.
